US00D822019S

(12) **United States Design Patent** (10) **Patent No.:** **US D822,019 S**
Komulainen (45) **Date of Patent:** **** Jul. 3, 2018**

(54) **MODULE OF PERSONAL LIFESTYLE MONITORING AND MANAGEMENT DEVICE**

(71) Applicant: **Polar Electro Oy**, Kempele (FI)

(72) Inventor: **Olli Komulainen**, Oulu (FI)

(73) Assignee: **Polar Electro Oy**, Kempele (FI)

(**) Term: **15 Years**

(21) Appl. No.: **29/552,808**

(22) Filed: **Jan. 26, 2016**

(30) **Foreign Application Priority Data**

Dec. 10, 2015 (EM) 002904698-0003

(57) **CLAIM**

The ornamental design for a module of personal lifestyle monitoring and management device, as shown and described.

DESCRIPTION

FIG. 1 is a left isometric view of the module of personal lifestyle monitoring and management device;

FIG. 2 is a left-side view of the module of personal lifestyle monitoring and management device;

FIG. 3 is a right isometric view of the module of personal lifestyle monitoring and management device;

FIG. 4 is a right-side view of the module of personal lifestyle monitoring and management device;

FIG. 5 is a front view of the module of personal lifestyle monitoring and management device; and,

FIG. 6 is a rear view of the module of personal lifestyle monitoring and management device.

The broken lines shown in the drawings illustrate portions of the module of personal lifestyle monitoring and management device that form no part of the claimed design.

1 Claim, 6 Drawing Sheets
